EDWARD L. WATROUS, DECEASED, LATE OF EL PASO, TEXAS, BY AGNES B. WATROUS,
EXECUTRIX, OF EVANSTON, ILLINOIS.

COATING APPARATUS AND METHOD.

1,350,481.

Specification of Letters Patent. Patented Aug. 24, 1920.

Application filed September 20, 1919. Serial No. 325,254.

To all whom it may concern:

Be it known that EDWARD L. WATROUS, deceased, late a citizen of the United States, formerly residing at El Paso, in the county 5 of El Paso and State of Texas, did invent new and useful Improvements in Coating Apparatus and Methods, of which the following is the specification.

This invention relates to a coating apparatus and method and more particularly to such as applied to galvanizing or otherwise coating lengthy materials such as pipes, bars, and the like.

Among the objects of this invention are 15 to provide an improved method and apparatus for coating elongated articles such as pipes, bars, or the like, and of such nature that the pipes, bars or the like may be placed in a rack, the rack and its contents 20 dipped in the coating bath and then subjected to centrifugal force whereby the pipes, bars or the like will present a smooth surface free from undesirable protuberances or excrescences; further to provide novel 25 means for subjecting the freshly coated said articles to centrifugal force to throw off all excess coating material therefrom while still plastic; further, to substantially eliminate the necessity of counterweights for the 30 revolving parts; further, to provide a removable rack for holding the articles while being dipped and which with its contents can be quickly and readily applied to or removed from the shaft; further, to form such 35 rack of spaced apart plates of substantially disk formation and having apertures to receive the articles being treated; further, to form said plates of progressively increasing diameter and an additional plate to act as 40 a thrust plate; further, to provide novel means for locking the rack to the rotating shaft; and such further objects, advantages, and capabilities as will later more fully appear.

45 This invention further resides in the combination, construction, and arrangement of parts illustrated in the accompanying drawings, and while there is shown therein a preferred embodiment, it is to be understood 50 that the same is susceptible of modification and change without departing from the spirit of the invention.

As stated in a co-pending application, Serial No. 212,908, of which this constitutes an 55 improvement, pipes, bars and the like when

galvanized or otherwise coated by the formerly known methods and apparatus have possessed certain objectionable features, among the more prominent of which would be the formation of projections and rough 60 surfaces upon the exterior of the pipe, due to the coating material gathering on the underside of the pipe and there solidifying. The present invention entirely overcomes 65 these objections and makes possible the 70 coating of such pipes, bars, and the like in a manner that results in the formation of an entirely smooth coating surface devoid of the above mentioned objectionable projections and rough portions. 75

Referring to the drawings, Figure 1 is a side elevation of the improved device showing the pipes, bars or the like in dotted lines.

Fig. 2 is a transverse vertical section of 75 Fig. 1 taken through the shaft between the end plate and the right hand journal box and support.

In the drawings, it will be seen that there are provided suitably spaced standards or 80 supports 1, in which is journaled the shaft 2 carrying upon one of its ends the pulley 3, over which travels the belt 4 driven from any suitable source of motive power. Detachably mounted upon the shaft 2 is the 85 rack designated generally at A and comprising the spaced apart plates 5 and the end plate or thrust plate 6 all of which plates are rigidly secured together in suitably spaced relation by means of the rods 90 7 carrying thereon the threaded nuts 8 in position to clamp between each pair of nuts one of the above mentioned plates.

The plates 5 are formed with a suitable number of perforations 9 and a slot 10 of 95 sufficient width to slip over the shaft 2, and of such a depth that when the end of the slot contacts with the shaft 2 the plates and the shaft 2 will be concentric. Along the marginal portions of the slot 10 the plates 100 5 are provided with a strengthening flange 11, which flange from the mid-position of the end of the slot continues diametrically to the circumference of the circle, on which the plate is formed. The thrust plate 6 is 105 formed similarly to plates 5 with the exception that it does not have the apertures 9, and is reversely positioned on the shaft 2, that is so as to bring its plane face toward the nearest plates 5. 110

By virtue of the slots 10 the rack which, as stated above, comprises plates 5 and 6 rigidly secured together by the rods 7 can be positioned upon the shaft 2 or removed therefrom as a unit when desired. For the purpose of securely locking the rack A to the shaft 2 I have provided the pivoted locking lever 12, of which there may be any suitable number desired. This locking lever, as seen in Fig-2, is pivotally mounted in a suitable slot in the shaft 2 by means of the pivot 13, about which it may rotate in a plane passing longitudinally through the center of the shaft. The upper or locking end of this lever is bifurcated as shown at 14, thus providing a catch that may straddle that portion of the flange extending from the slot to the circumference of the plates. This feature gives additional resistance to any tendency of the rack to rotate with relation to the shaft. The lower end 15 of the locking lever 12 it is to be noted extends a substantial distance to one side of the pivot 13, as a result of which this end 15 will under the action of centrifugal force during rotation of the shaft 2 tend to move outwardly, and thus more securely force the bifurcated catch 14 into engagement with the upper surface of the flange 11 at the end of the slot 10.

In the operation of the improved apparatus and the carrying out of the method of galvanizing pipe, bars, or the like, the pipes, bars, or the like are placed in the rack A by inserting them through the apertures 9 until their ends come in contact with the thrust plate 6, which will, as is obvious bring the ends in alinement. After the apertures have been filled with pipes, bars, or the like the entire rack and its contents will be dipped in a coating bath, such as spelter when galvanizing, or other suitable bath for other forms of coating, after which the rack and its contents will be withdrawn from the bath and placed upon the shaft 2 by passing the slots 10 thereover. As the portion of the flanges 11 at the ends of the slots 10 contact with the beveled faces of the catch 14, this catch as is obvious will be forced away to permit this flange to pass under the bottom edge of the lips of these catch, after which by the force of gravity acting upon the ends 15 the catches will automatically move into locking position, thus firmly securing the rack upon the shaft and causing it to rotate therewith when said shaft is rotated. The shaft will then be rotated at a suitable speed to throw, by action of centrifugal force, any excess coating material from the pipes, bars, or the like as a result of which the finished coating remaining on the pipes when the operation is completed will be smooth and free from undesirable projections or excrescences. Upon completion of the operation, the locking levers 12 may be released and the rack 60 and its contents removed from the shaft pre-

paratory to the removal of the finished pipes, bars, or the like and repetition of the coating operation.

It will be noted that the location of the apertures 9 within the plates 5 is such as to eliminate the necessity of any additional counterweights due to the substantially equal distribution of weight in the revolving parts. While the apertures are shown as being round, it is obvious that, if desired, they may be made of any other configuration whereby to accommodate bars of other shapes such for instance as angle bars, or the like. It will be further understood that if desired a suitable shield may be positioned around the revolving rack A whereby to prevent the undesirable flying of spelter or other coating material.

It is to be further noted that the plates 5 progressively increase in diameter and that the apertures 9 are so aligned that the pipes, bars, or the like when inserted therein will lie at an angle to the longitudinal axis of the shaft 2. The purpose of this is, when pipes are being galvanized or otherwise coated, to cause any of the coating material that may have entered the inside of the pipe to be thrown out of the end thereof, as a result of the centrifugal action, to which they are subjected. Should these pipes be placed parallel with the shaft, any coating material that may enter the inside thereof would be held therein during rotation by the walls of the pipe. However, by placing the pipes at an angle the coating material which may have entered the inside of the pipe, as is obvious, will be forced out of the end of the pipe, due to the centrifugal force set up by the rotation of the apparatus.

Having now described the invention, what is claimed is:

1. In apparatus of the class described means for subjecting freshly coated pipes, bars or the like to centrifugal action, said means comprising a rotatable shaft, a plurality of perforated disk-like plates spaced on said shaft and each provided with a plurality of spaced perforations, and means for rotating said shaft and plates.

2. In apparatus of the class described a rotatable shaft, a plurality of plates spaced along said shaft and provided with perforations adapted to receive pipes, bar, or the like, the location of the apertures being such that when said pipes, bars or the like are placed therein and said shaft and plates rotated any necessity for counterweights will be eliminated, and means for rotating said shaft.

3. In apparatus for subjecting freshly coated pipes, bars or the like to centrifugal action, a rotatable shaft, a detachable rack including a plurality of members adapted to hold said articles while being dipped and then immediately placed on said shaft with

- its freshly coated contents the articles to be coated extending through perforations in successive rack members, and means for rotating said shaft, rack and contents.
- 5 4. In apparatus for subjecting freshly coated pipes, bars or the like to centrifugal action, a rotatable shaft, a rack for holding said articles while being dipped, said rack having means to permit it being readily placed on said shaft with its freshly coated pipes, bars or the like, means for locking said rack to said shaft, and means for rotating said shaft, rack and contents.
- 10 5. In apparatus for subjecting freshly coated pipes, bars or the like to centrifugal action, a rotatable shaft, a rack for holding said articles while being dipped, said rack having means to permit its being readily placed on said shaft with its freshly coated pipes, bars or the like, means for locking said rack to said shaft, and means for rotating said shaft, rack and contents, said locking means being more positively urged into locking engagement with said rack as the speed of rotation increases.
- 15 6. In apparatus for subjecting freshly coated pipes, bars and the like to centrifugal action, a shaft, a rack for receiving the articles to be coated and adapted to be readily placed upon or removed from said shaft, said rack comprising a plurality of perforated spaced apart plates, an imperforate thrust plate forming one end of said rack, and means for rigidly securing said 20 perforated plates and thrust plate in spaced apart relation, and means for rotating said shaft.
- 25 7. In apparatus of the class described a shaft, a rack detachably mounted on said shaft, said rack comprising a plurality of rigidly connected spaced apart apertured plates and a thrust plate, a locking lever pivotally mounted on said shaft and having a catch for locking said rack to said shaft and an extended end adapted to be urged outwardly by centrifugal force to increase the locking action of said catch, and means for rotating said shaft.
- 30 8. In apparatus of the class described a shaft, a rack detachably mounted on said shaft, said rack comprising spaced apart plates having alined apertures, said plates progressively increasing in diameter from one end of said rack to the other and being rigidly connected together, and means for rotating said shaft.
- 35 9. In apparatus of the class described a shaft, a rack detachably mounted on said shaft, said rack comprising spaced apart plates having alined apertures, said plates progressively increasing in diameter from one end of said rack to the other and being rigidly connected together, and means for rotating said shaft, said rack also compris-

ing at one end a thrust plate, the plates of said rack having alined slots adapted to take over said shaft.

10. In apparatus of the class described a shaft, a rack detachably mounted on said shaft, said rack comprising spaced apart plates having alined apertures, said plates progressively increasing in diameter from one end of said rack to the other and being rigidly connected together, and means for rotating said shaft, said rack also comprising at one end a thrust plate, the plates of said rack having alined slots adapted to take over said shaft, releasable means for locking said rack to said shaft, and means for rotating said shaft.

11. In apparatus of the class described, a shaft, a rack detachably mounted on said shaft, said rack comprising spaced apart plates having alined apertures, said plates progressively increasing in diameter from one end of said rack to the other and being rigidly connected together, the apertures being arranged in the plates in the form of frustums of cones, and means for rotating said shaft.

12. In apparatus of the class described, a shaft, a rack detachably mounted on said shaft, said rack comprising spaced apart plates having alined apertures, said plates progressively increasing in diameter from one end of said rack to the other and being rigidly connected together, the apertures being arranged in plates in a frusto-conical form, and means for rotating said shaft, said rack also comprising at one end a thrust plate, the plates of said rack having alined slots adapted to take over said shaft.

13. In apparatus of the class described, a shaft, a rack detachably mounted on said shaft, said rack comprising spaced apart plates having alined apertures, the apertures being arranged in the plates in the form of a frustum of a cone, and means for rotating said shaft.

14. The method of galvanizing pipes, bars, and the like which comprises placing in a rack the pipes, bars, and the like, dipping said rack and contents in a coating bath, removing them from said bath and immediately placing said rack and contents on a shaft and rotating said shaft, rack, and contents to throw any excess coating material from said pipes, bars, or the like to produce a smooth coating surface on the articles to be coated.

In witness whereof, I hereunto subscribe my name to this specification in the presence of one witness.

AGNES B. WATROUS,
*Executrix of the will of Edward L. Watrous,
deceased.*
